(57) **CLAIM**

The ornamental design for a light fixture as shown and described.

DESCRIPTION

FIG. 1 is a top perspective view of a light fixture;

FIG. 2 is a bottom perspective view thereof;

FIG. 3 is a front view thereof;

FIG. 4 is a top view thereof; and,

FIG. 5 is a bottom view thereof.

The right side view, left side view, and rear view are mirror images of the front view thereof. The broken lines in the figures are for the purpose of illustrating the light fixture mount for the light fixture and form no part of the claimed design.
